UNITED STATES PATENT OFFICE.

STACY B. HASELTINE, OF CHICAGO, ILLINOIS, ASSIGNOR TO WILLIAM H. MINER, OF CHICAGO, ILLINOIS.

DRAFT-RIGGING FOR RAILWAY-CARS.

1,136,008.

Specification of Letters Patent. Patented Apr. 20, 1915.

Application filed June 12, 1913, Serial No. 773,333. Renewed August 12, 1914. Serial No. 856,485.

To all whom it may concern:

Be it known that I, STACY B. HASELTINE, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of high cushioning capacity. 15 In the drawings forming a part of this specification—Figure 1 is a side elevation partly in longitudinal section on line 1—1 of Fig. 2 of a draft rigging embodying my invention; Fig. 2 is a plan view partly in horizontal section on line 2—2 of Fig. 1, and showing the normal position of the parts; Fig. 3 is a plan view partly in horizontal section showing the position of the parts when fully compressed; Fig. 4 is a transverse section on line 4—4 of Fig. 1, one 20 side of the same, however, showing the spring cap removed; Fig. 5 is a plan view partly in horizontal section showing the position of the parts when fully compressed 25 in draft.

Referring to the drawings 6, 6 represent draft sills or parts of the car frame to which the draft rigging is applied, the same being provided with rear stop shoulders 7, 7, intermediate stop shoulders 8, 8 and front stop shoulders 9, 9.

10 represents the end sill, 11 the draw bar carry iron, 13 the tie plate suitably secured to the draft sills, preferably by the bolts 40 14, 14, 15 the draw bar, 16 the draft yoke secured thereto, 17 the draft gear mounted within the yoke.

The inner shell 18 of the draft gear is 45 preferably cylindrical in shape or circular in cross section, open at its forward end and closed at its rear end by the preferably integral plate 19. Laterally extended from the rear end of said shell are plates 20, 20, the same being preferably continuations of the plate 19 and integral therewith, the same serving as a rear follower and adapted to engage the rear stop members 7, 7.

Within the inner shell is disposed friction mechanism 21, the friction shoes 22, 22 thereof being preferably three in number

and annularly arranged, each having an outer friction face 23 to engage the internal friction face 24 of the inner shell. A wedge 25 is mounted within the friction shoes and adapted to spread the same, the said wedge 60 being provided with wedging faces 26, 26 equaling in number the friction shoes. Between each wedging face 26 of the wedge 25 and each of the friction shoes there is provided an antifriction roller 27. The wedge 65 25 is forwardly provided with a recess 28 to receive the head 29 of the connecting rod 30 which passes through the perforation 31 in said wedge, and through a perforation 32 in the internal follower 33, the said internal 70 follower being provided with a recess 34 to receive the nut 35 of said connecting rod.

The internal follower 33 is a block like member forwardly provided with a forwardly extending flange or collar 36 within 75 which is mounted a preliminary spring 37 of low capacity in comparison with the other springs of the draft gear hereinafter described. The internal follower 33 is provided with a transverse slot 38 to receive 80 the key 39, which extends through the elongated slots 40 provided in either side of the inner shell 18. An outer shell 41 surrounds the inner shell 18, the said outer shell being provided at either side with the slots 42 85 registering with the slots 40 of the inner shell, and adapted to receive the ends of the key 39 therein.

The outer shell 41 is forwardly provided with the lateral wings 43, the same being 90 preferably integral with the said shell, between which wings and the plates 20, 20 of the inner shell are seated without the shell and at either side thereof the main springs 44. The main springs 44 each preferably 95 consists of an outer spring 45 and an inner spring 46 nested therein. The wings 43 of the outer shell are in normal position of the gear slightly removed from the intermediate stop shoulders 8, 8, the space between them 100 in such normal position being indicated by the numerals 47, 47 in Fig. 2 of the drawings. The slots 40 provided in the inner shell are of sufficient length to permit the reciprocating movement of the key 39 there- 105 in. 48 represents the front follower adapted to engage the front stop shoulders 9, 9, and in engagement at its rear face with the wedge 25 of the friction mechanism.

On rearward movement of the draw bar the 110

inner shell is stopped against rearward movement through the engagement of the plates 20 against the rear stop shoulders 7, 7. The rearward travel of the front follower 48 forces the wedge 25 and the friction shoes 22 rearwardly, compressing the preliminary spring against the internal follower 33 until the collar 36 of the internal follower 33 engages the friction shoes, thus limiting the compression of the preliminary spring. Upon further compression the internal follower 33 moves rearwardly within the inner shell 18, the key 39 therein sliding rearwardly in the lateral slots 40, 40 of the inner shell, and drawing the outer shell rearwardly, thus compressing the main springs between the wings 43 of the outer shell and the plate 20 of the inner shell. Meanwhile the spreading action of the wedge within the friction shoes forces the friction shoes into frictional engagement with the inner shell.

On full compression of the parts the front follower 48 engages the forward end of the inner shell, as illustrated in Fig. 3 of the drawings, and the key 39 clears the rear ends of the slots 40 in the inner shell.

On forward movement of the draw bar the draft yoke draws the inner shell forwardly, the pressure of the main springs between the wings 43 of the outer shell and the plates 30 of the inner shell maintaining the inner and outer shells in the same relative position with the front edge of the key 39 against the forward end of the slots 40 in the inner shell while the preliminary spring is being compressed between the friction shoes and the internal follower.

When the collar 36 of the internal follower engages the friction shoes the wings 43 of the outer shell engage the intermediate stop shoulders 8, 8, and on further forward movement of the inner shell the main springs are compressed, the key 39 through the internal follower remaining stationary, the slots 40 in the inner shell moving forwardly without strain upon the said key 39. The inner shell by reason of the slight pressure exerted against the rear ends of the friction shoes travels forwardly about 50 said shoes without the same being brought into compression resisting action on said forward movement of the draw bar. Thus on forward movement of the draw bar the springs alone are in compression resisting action, while in rearward movement of the draw bar the springs and friction mechanism are both in action.

I claim:

1. In a draft gear, an inner shell, friction mechanism in said shell, an outer shell, enclosing the inner shell, front and rear followers, a key and main springs, the outer shell being provided with laterally extended wings, the main springs being seated between said wings and the rear follower, and

the key connecting the outer shell to the mechanism in the inner shell.

2. In a draft gear, outer and inner reciprocating shells, wings laterally extended from each of said shells, main springs seated between the wings of the outer shell and the wings of the inner shell, friction mechanism within the inner shell, and a key connecting the outer shell to the mechanism in the inner shell. 70

3. In a draft gear, in combination, outer and inner reciprocating shells, wings laterally extended from each of said shells, main springs seated between the wings of the outer shell and the wings of the inner shell, friction mechanism and an internal follower within the inner shell, and a key engaging the internal follower to the outer shell. 75

4. In a draft gear, in combination, an outer shell and an inner shell reciprocating therein, each of said shelves being provided with laterally extended wings, main springs seated between the wings of the outer shell and the wings of the inner shell, a wedge, friction shoes and an internal follower within the inner shell a preliminary spring seated between the internal follower and the friction shoes, and a key engaging the internal follower to the outer shell. 85

5. In a draft gear, in combination, an outer shell provided with lateral wings, an inner shell reciprocating therein provided with lateral wings, main springs at either side of the outer shell seated between the wings of the outer shell and the wings of the inner shell, friction shoes, a wedge and an internal follower within the inner shell, a key engaging the internal follower to the outer shell, the inner shell being provided with slots for the passage of said key. 95

6. In a draft gear, outer and inner reciprocating shells, wings extended from each of said shells, main springs seated between the wings of the outer shell and the wings of the inner shell, friction mechanism within the inner shell, and means connecting the friction mechanism to the outer shell. 100

7. In a draft gear, in combination, outer and inner reciprocating shells, wings laterally extended from each of said shells, main springs seated between the wings of the outer shell and the wings of the inner shell, friction mechanism and an internal follower within the inner shell, registering slots in the inner and outer shell, and a key passing through said slots and engaging the outer shell to the internal follower. 115

8. In a draft gear, in combination, an outer shell and an inner shell reciprocating therein, each of said shells being provided with laterally extended wings, main springs seated between the wings of the outer shell and the wings of the inner shell, a wedge, friction shoes and an internal follower within the inner shell, a preliminary spring 125

seated between the internal follower and the friction shoes, a key engaging the internal follower to the outer shell, the internal follower being provided with means to limit 5 the compression of the preliminary spring.

9. In a draft gear, in combination, an outer shell and an inner shell reciprocating therein, each of said shells being provided with laterally extended wings, main springs seated between the wings of the outer shell 10 and the wings of the inner shell, a wedge, friction shoes and an internal follower within the inner shell, a key engaging the internal follower to the outer shell, a preliminary spring seated between the internal follower and the friction shoes, the internal follower being provided with a forwardly extending collar to limit the compression of the preliminary spring, the inner shell 15 being provided with slots for the passage of the key; said slots being rearwardly extended to permit the relative movement of the inner and outer shells after the compression of the preliminary spring.

25 10. In a draft gear, in combination, an

outer shell, an inner shell reciprocating therein, each of said shells being provided with laterally extended wings, main springs seated between the wings of the outer shell and the wings of the inner shell, a wedge, 30 friction shoes and an internal follower within the inner shell, means rigidly engaging the outer shell to the internal follower, the inner shell being provided with longitudinally extended slots to permit the wings of 35 the outer shell and the wings of the inner shell to approach each other and compress the main springs between them.

11. In a draft gear, an inner shell, an outer shell surrounding the same, friction 40 mechanism in the inner shell, wings laterally extended from each of said shells, main springs seated between said wings, and means connecting the friction mechanism to the outer shell.
